CLAIM

The ornamental design for a docking station for receiving a portable computer, as shown and described.

DESCRIPTION

FIG. 1 is a reduced top front and right side perspective view of a docking station for receiving a portable computer showing our new design;

FIG. 2 is a front elevational view thereof;

FIG. 3 is a left side elevational view thereof with the lock shown in its open position;

FIG. 4 is a left side elevational view thereof with the lock shown in its closed position;

FIG. 5 is a right side elevational view thereof;

FIG. 6 is a rear elevational view thereof;

FIG. 7 is a bottom plan view thereof; and,

FIG. 8 is a top plan view thereof.

FIG. 1

FIG. 2

FIG. 3

FIG. 4

FIG. 5

FIG. 6

FIG. 7

FIG. 8
